MOUNTING DEVICE FOR GLAZING UNITS

George A. Leighton, Toledo, Ohio, assignor to
 Libbey-Owens-Ford Glass Company, Toledo,
 Ohio, a corporation of Ohio.

Application October 13, 1949, Serial No. 121,207

1 Claim. (Cl. 20—56.4)

1

The present invention relates broadly to the art of glass glazing and more particularly to an improved device for use in the mounting of multiple glass sheet glazing units.

As is well known, multiple sheet glazing units include two or more sheets of glass secured together to produce a unitary structure and, because of this, their manner of installation departs considerably from the method conventionally employed in glazing single lights of glass. Typical of such units is the one being manufactured and sold by the assignee company under the trade-mark "Thermopane." In this particular unit, the glass sheets are secured in properly spaced, parallel relationship by metallic separator means arranged between the glass sheets and soldered to metallic coatings, provided around the marginal portions thereof, to form a hermetically sealed structure.

When installing units of this type in a window opening or sash frame, the bottom edges thereof are ordinarily secured in a bed of glazing compound. In the case of large units, it has been considered necessary to employ special soft-surface setting blocks which maintain the unit out of actual contact with the framing structure.

Briefly stated, according to the present invention, there is provided a novel mounting device in the form of a specially formed spring clip, a plurality of which may be resiliently attached to a double glazed unit, at spaced intervals around the edges thereof, at the time of its installation. Being directly associated with the glass sheets of said unit, these clips, in the case of large units, eliminate the necessity for the use of the usual setting blocks and, at the same time, afford positive protection for the bottom edge of the unit as it is installed in the sash frame.

When the glazing unit is installed in a substantially vertical position, each mounting clip, by reason of its novel construction, will independently support each of the glass sheets of the double glazing unit at their lower edges so that, with a plurality of the clips, surface irregularities of the sash or the unit will be compensated for and the weight of the unit's mass equally distributed.

It is an aim of the invention to provide an improved mounting clip for multiple glazing units which affords spring type, separate supporting surfaces for the glass sheets of such units whereby any unevenness in the sash frame, either transversely or longitudinally, will be compensated for and the weight of the unit evenly and uniformly distributed throughout the frame, thereby reducing or eliminating the creation of strains and stresses in the unit which would act to rupture the seal thereof or cause breakage of the glass.

2

Another object of the invention is to provide a mounting clip for multiple glazing units associated with such units in such a manner as to protect the bottom edges from contact with the sash frame without the use of setting blocks.

Another object of the invention is to provide a mounting clip of novel construction for multiple glazing units, said clip being so formed as to equally space the double glazing unit within 10 a sash frame thereby permitting equalized fill of glazing compound with respect to either face of the unit and the adjacent edges of the frame and consequently reducing the time required for glazing.

15 A further object of the invention is to provide a mounting clip of the character described, so formed that, in cooperating association with similarly arranged clips, balanced spacing of the unit within the rabbeted portion of a sash or window 20 framing structure will be effected whereby the glazing compound may thoroughly seal said unit around its entire perimeter.

25 A further object of the invention is to provide a mounting clip of the character described adapted to frictionally grip the surface of a sash frame thereby sustaining the multiple glazing unit from shifting and without the use of points or other securing devices.

30 A still further object of the invention is to provide a mounting device of multiple glazing units that is characterized by its exceedingly efficient functioning, ease of installation, strength of construction and economy of manufacture.

35 Other objects and advantages of the invention will become more apparent during the course of the following description, when taken in connection with the accompanying drawings.

In the drawings, wherein like numerals are employed to designate like parts throughout the 40 same:

Fig. 1 is a front elevation illustrating a window glazed with the clips of the invention;

Fig. 2 is a perspective view of one form of 45 double glazing unit showing the mounting clips arranged thereon;

Fig. 3 is a perspective of a preferred form of mounting clip constructed in accordance with the invention;

Fig. 4 is a vertical, transverse section on line 50 4—4 of Fig. 1;

Fig. 5 is a vertical, longitudinal section on line 55 5—5 of Fig. 4; and

Fig. 6 is a fragmentary detail of a modified form of gripping means for the mounting clip.

With reference now to the drawings and particularly to Figs. 1 and 4, there is disclosed a window, the panes of which are composed of multiple glazing units 9, mounted in a sash 10 by the spring clips 11 of the invention. By way 60 of example, and in nowise to limit the scope of

the invention, the window sash or frame **10** in which the units **9** are mounted has been illustrated as a conventional metal sash, movably or stationarily arranged within the window opening **12**.

The multiple glazing unit **9**, as shown, comprises two sheets of glass **13** and **14** (Fig. 4) spaced from one another to provide an insulating space **15** therebetween. Arranged between the glass sheets **13** and **14** and soldered to metallic coatings **16** provided around their marginal areas, is a metallic separator strip **17**. Although there has been illustrated here, by way of example, a type of multiple glazing unit, manufactured and sold by the assignee company under the trademark "Thermopane" (more particularly disclosed and claimed in Patent No. 2,235,680, dated March 18, 1941), it is to be understood that the invention may be used in the mounting of other types of multiple or double glazing units; also that it is adapted to the mounting of units comprising three or more sheets of glass.

It will be noted from Fig. 4 that it is possible to mount a double glazed unit **9** in a window frame **10** with the clips **11** as the sole mechanical mounting means. Heretofore, when installing "Thermopane" units of a size necessary for large, single sashes, picture or store windows and in which lights over 80 united inches were employed, it was considered necessary that they be supported on soft surface setting blocks. Such blocks were made of soft rot-proofed wood, soft lead, or of steel or aluminum with soft lead tops, and were required to be of the same width as the thickness of the unit to be glazed. The mounting blocks had to be located on the sash or frame to sustain the unit above and substantially level on the sash. They were located in place before the installation of the glazing unit and constituted an additional expense, and time-consuming factor, in the glazing procedure.

According to the present invention, however, and by employing the novel glazing clips **11**, the use of setting blocks can be entirely eliminated, with a corresponding reduction in cost, glazing time and number of mechanical glazing devices required.

The special spring type glazing clip of the invention can best be seen in Fig. 3. In its preferred form, it is substantially U-shaped, being provided with upwardly directed sides **18** and **19** rising convergently from the central web or base **20**. The clip is preferably formed of thin, tempered steel plate and may be, by way of example, of 28 gauge medium carbon steel which may be cadmium plated or cement coated according to trade demands. When the sides **18** and **19** are struck or otherwise bent from the base **20**, the elasticity of the metal supplies a desired amount of resiliency when the clip is operatively associated with the double glazing unit. The sides **18** and **19** thus constitute opposed gripping portions of the clip and to increase the effectiveness of their action, the outer edges **21** are spaced apart a distance slightly less than the thickness of the unit with which the clip is to be employed. These outer edges **21** are suitably rolled or bent over, as at **22**, so that the engaging surfaces will be provided over a relatively smooth, continuing area.

By reason of the inward inclination of the sides **18** and **19**, the base **20** is considerably wider between the corner areas **23** at the juncture of the sides and the base. The corners **23** on their exterior surfaces may thus provide shoulders, as

indicated at **24**, which serve to locate and space the unit **9** from any portion of the sash frame, as will be more fully hereinafter described.

In the base **20**, and preferably equally spaced between the ends thereof, are a pair of tongues **25** and **26**. The tongues are struck from the base **20** so as to project diagonally upward from the bend areas **27** and **28** of their formation. Preferably the tongues **25** and **26** rise from the opposite corner areas **23** of the base **20** and so that the tongue **25** will be diagonally directed toward the side **19** while the tongue **26** will extend toward the side **18**. The free end **29** of each tongue is suitably arched, as at **30**, to provide ample support or bearing surface upon which a glass sheet of the double glazing unit may be supported. Since the tongues are adapted to flex along their bend areas, they actually are spring leaves flexible about their anchored portion.

As shown in Fig. 3, the end areas **31** of the base may be pierced or otherwise ruptured to create protruding friction areas **32** that are forcible, when the clips are located on a portion of the sash, into the material thereof, or the surface coating thereon. As will be noted in Figs. 3 and 5, the protrusions **32** act to frictionally hold the clips in position and cooperate, at the bottom and top of the unit, to sustain said unit from displacement and against ordinary pressures to be withstood by window enclosing structures. In Fig. 6, there is shown a slightly modified type of friction area which is embodied in an extended tip or prong **33** that is struck from the marginal edges of the clip at each end so as to project outwardly and downwardly when the sides of the clip are bent upwardly with reference to the base.

Prior to installation of a double glazing unit **9** into a sash or frame, such as the frame **10**, mounting clips **11** are arranged along the bottom and top edges, as is shown in Fig. 2. In so locating these clips, the outer end **21** of one side is placed over the edge of the unit and the opposite side is sufficiently flexed until the same can be snapped over the opposite edge of the unit. The clip is then forced inwardly until the tongues **25** and **26** engage the edge surfaces of the glass sheets, such as the sheets **13** and **14**. As shown in Fig. 4, the arched surface **30** of one tongue **25** will now engage one glass sheet **13** of the unit **9** while the surface **30** of the oppositely directed tongue **26** will engage the other glass sheet **14**. In the case of thicker units, such as may be comprised of three or four sheets of glass, the accommodating size of mounting clip will locate the arched surface **30** of each tongue so that it will engage the outer sheet on each side of the unit and thus adequately support the same.

The mounting clips **11**, now associated with the unit **9**, and particularly along its bottom edge are placed in the bed of glazing compound on the sash frame. As herein shown, the sash frame **10** is of the conventional metal construction having a T-section which comprises a horizontally disposed leg **34** and a vertical web **35** which constitutes the face of the frame; however, it will be quite apparent that various other structures, such as wood sashes having a rabbed glass receiving section are contemplated in the use of the mounting clips. In placing the unit within the open area of the sash and, by way of example, on the horizontal leg **34**, the clips act to effectively protect the unit from contact thereby reducing or eliminating any possibility of chipping or fracture. As previously set forth, in the case of large size glazing units,

the lower clips 11 also reduce the glazing time by eliminating the use of setting blocks upon which the units have heretofore been supported.

The upper edge of the unit is now directed inwardly of the sash; in this instance, the upper mounting clips 11 are employed as pressure points to "spring" the unit into a vertical position within the frame. Since the bases 20 of the clips are spaced, by the resiliency of the tongues 25 and 26, from the edges of the unit; in one instance, said unit will now be supported above the top surface of a horizontal leg 34 of the sash frame while in the other, the base sections of the clips at the top of the unit and adjacent the under surface of a leg 34 are adapted to absorb the force of the inward thrust as said unit is moved into a vertical position. In either event, the inward sliding displacement of the clips with respect to the double glazing unit will be compensated for by individual flexure of the tongues 25 and 26 and the unit 9 eventually will become balanced vertically within the frame.

As particularly shown in Fig. 4, a double glazing unit 9 is thus supported on the leg 34 of the frame 10 by the clips 11. Upon further inward movement, by pressure equally distributed at the top and bottom of the unit, the bed of glazing compound, as indicated at 36, will be forced or squeezed out until the shoulders 24 of the clip contact the inner face of the web of the frame 10. This will ordinarily effect a reduction in the amount of glazing compound required by assuring a minimum thickness of compound throughout the installation.

The upper and lower edges of the unit being provided with clips 11 and preferably near the vertically disposed sides of the unit, the contacting of the shoulders 24 of the several clips 11 automatically assures an even space between the unit and the frame at all points without manual adjustment and repeated shifting of the unit. A continuous seal of the compound 36 is thus also established to thoroughly enclose the unit and without detraction of appearance by irregular filling of the compound.

As the unit is finally placed in the sash frame, its normal weight reacts upon the tongues 25 and 26 to substantially balance the unit since each of the glass sheets 13 and 14 is independently mounted and one or the other will individually affect the flexing of the tongue with which it is associated. Moreover, when the leg 34 of the frame 10 is not substantially horizontal or parallel to the unit, either longitudinally or transversely, the resilient relation of the tongues 25 and 26 to the base 20 causes the base to suitably locate itself on the surface of the leg 34 while the tongues rise or are depressed until the weight of the unit is evenly distributed across and between the bottom edges of the glass sheets. Consequently, the entire weight of the unit can not be borne by one sheet of glass, and strains or stresses, such as would rupture the seal between the sheets, will not be set up. This is particularly important in the case of an hermetically sealed unit as here shown and where the separator strip 17 is soldered to the metallic coatings 16 around the marginal edges of the glass sheets 13 and 14. In the event of rupture of the hermetic seal in such a unit, the effectiveness of the unit is greatly reduced, and the space 15 is exposed to entry and circulation of air, moisture

and dust which practically destroys the efficiency and insulating effect of the structure. In extreme cases, the supporting of such a unit by one sheet only may cause fracture of the glass and thus render the multiple glazing unit entirely useless.

When the mounting clips 11 are finally settled in relation to the double glazing unit and contact with the frame, the protrusions 32 have become forced into the surface or surface coating of the leg 34 of the frame 10. Since each clip has a plurality of such friction areas, each in engagement with said leg, their multiplicity materially increases the resistance normally required to sustain the unit from undue lateral pressure. In fact, when employed in connection with wood sash constructions, the protruding areas will enter even more effectively to hold the unit. The installation is completed in the usual manner by a fill of glazing compound as shown at 37 in the drawings.

It is to be understood that the form of the invention herewith shown and described is to be taken as a preferred embodiment of the same, but that various changes in the shape, size and arrangement of parts may be resorted to without departing from the spirit of the invention or the scope of the subjoined claim.

I claim:

- 30 A mounting clip for a multiple glass sheet glazing unit of the type including two sheets of glass which are secured together in spaced relation by separator means arranged between said sheets around the marginal edge portions thereof, said
 35 clip comprising a base, resilient side portions extending longitudinally of the base and convergently upward therefrom and adapted to actively receive the glazing unit therebetween and to actively grip the two glass sheets thereof, a pair
 40 of longitudinally spaced and oppositely directed tongues of substantially equal length struck from the base of the clip and extending transversely to and diagonally upward from said base in substantially equal angular relation thereto and toward opposite side portions, and a bearing surface at the upwardly disposed end of each of said tongues, the bearing surface of one of said oppositely disposed tongues being disposed adjacent one of said side portions and the bearing
 50 surface of the other tongue disposed adjacent the other side portion, said first-mentioned bearing surface being adapted to resiliently support the edge of one glass sheet gripped by its adjacent side portion and said second-mentioned
 55 bearing surface being adapted to resiliently support the edge of the other glass sheet gripped by its adjacent side portion.

GEORGE A. LEIGHTON.
